UNITED STATES PATENT OFFICE

THOMAS N. DERBY, OF ROUND LAKE, NEW YORK, ASSIGNOR, BY MESNE ASSIGNMENTS,
TO SAID THOMAS N. DERBY AND ELWIN S. BENTLEY

CAP AND POURER

Application filed August 30, 1929. Serial No. 389,511.

This invention relates to improvements in bottle closures and particularly pouring closures adapted for use in connection with milk wherein the closure has the function of selectively permitting the pouring of either 5 milk or cream from the bottle.

It is an object of the invention to provide a closure which will be securely held in place upon the bottle and be liquid-tight with respect thereto and which will be provided with two openings spaced apart, one permitting the discharge of cream and the other the discharge of milk.

It is a further object of the invention to 15 provide an extremely simple construction for this purpose which can be utilized by the average housewife without difficulty and which can either by a permanent closure served with the milk bottle or an attachment 20 therefor.

Referring to the drawings,

Figure 1 is a top plan view.

Figure 2 is a view in side elevation.

Figure 3 is a sectional view, and

25 Figure 4 is another sectional view.

The closure may be stamped, cut or otherwise formed from material such as sheet metal, paper as flexible cardboard, celluloid or any one of a number of substances or compositions which can be regarded as thoroughly sanitary and having sufficient 30 rigidity.

In the present instance, there is illustrated a metal cap at 10, which is provided with cut 35 away portions forming spaced projections 11 which are curved as shown to fit about the lip of the usual standard milk bottle, so as to securely clamp the cap in place.

The base of the cap shown is circular, al- 40 though it may be square, rectangular or of irregular form and formed at a point between its diameter and the periphery is a triangular opening 12 which will be called the cream opening. In the formation of this 45 opening the metal is preferably struck from the base of the cap to form a pouring spout indicated at 13. It will be noted that the base of the struck-out portion is parallel with the diameter and that the opening is tapered up- 50 wardly. In this manner, the struck-out por-

tion 13 can be very easily concaved to serve as an effective pouring spout.

In the other half of the base of the cap and below the diameter thereof substantially mid-way between it and the circumference 55 is a relatively small circular opening indicated at 14. This opening which is in diametrical alignment with the larger opening 12, is adapted to be closed when cream is being poured through the opening 12 and 60 spout 13 and for this purpose, I provide a swinging closure indicated at 15, which it will be observed, is attached to the base of the cap by a rivet or stud 16, whereby the closure 14 may rotate about the cap, and cover and 65 uncover the opening 14. The pivoted closure or valve 15 has a portion thereof bent in as shown at 17 and this concave portion is adapted in the closed position of the valve to fit in the opening 14 in the cap to effectively 70 seal it.

Since in the present case, all of the parts are of thin metal, the closure itself will resiliently grip the lip of the bottle and the swinging or pivoted valve will likewise snap into 75 the opening 14 to effectively close it.

This, of course, would also be true with a closure of cardboard or celluloid of sufficient rigidity.

In the practical operation of the invention 80 the cap may be supplied with the milk bottle in the usual delivery of milk, although this is not contemplated, and the device is more to be regarded as an attachment for a milk bottle for use after the usual paper cap in 85 which it is delivered has been removed.

Arranged within the closure is a suitable washer of rubber or paper composition indicated at 18, which, when the cap is applied to the bottle, will effectively engage the bottle 90 lip to seal the contents from passing about the bottle between the cap and leaking down about the lip and sides.

A housewife having attached the present 95 invention to a milk bottle, may tilt the bottle after the manner shown in Figure 3 and since the cream being lighter is at the top, care need only be taken to the end that the pouring be slowly conducted until the cream level 100 has been discharged. In other words, it is

only necessary to tilt the bottle and watch until the cream content or so much of it as desired is discharged. The cream will come out smoothly through the opening 12 and be directed by the spout 13 as desired.

It will be noted that the opening 12 is so spaced with respect to the cap and the bottle and is of such area that it will substantially coincide with a portion of the opening in the 10 lip of the milk bottle, so that the cream will have an unobstructed passage. This is indicated in Figure 3 and while, of course, the present device is adapted for the standard milk bottle, the opening 12 and spout can be 15 moved to accommodate other sizes of bottles. It has been found that the opening can be successfully located by having its base or largest dimension parallel to the diameter of the cap and about mid-way between that diameter and the periphery of the cap. It is then only necessary to make the opening of such a depth that its curved edge or angular edges will coincide with the rounded edge of the interior of the lip of the bottle. This, as 20 previously stated, is shown in Figures 1 and 3. If all of the cream has been taken off, clearly the opening 12 and spout 13 can be used for removing the milk or most of it.

On the other hand, it is assumed that only 30 a portion of the cream is desired and that a quantity is left in the bottle. This being the case and it being desired to dispense milk from the bottle, it is only necessary for the housewife to again tilt the bottle, keeping the 35 cream level below the opening 12. This having been done, the closure 15 is moved on its pivot 16 to uncover the opening 14 when the milk constituting the lower stratum will pass out through the opening 14, as shown in Figure 4.

In this manner, all of the cream can be selectively taken from the bottle and substantially all of the milk can likewise be removed.

It will be seen that it is only necessary to 45 watch the extent of the strata of milk and cream, the cream being the lighter and uppermost stratum, while the milk being the heavier constitutes the lowermost one.

In other words, as shown in Figure 3, the 50 opening 14 will be closed when it is desired to skim the milk or take off the cream content, and when it is desired to take off the milk content and leave the cream in the bottle, the bottle will be tilted to bring the cream 55 level in a position where it will not pass out through the opening 12, and will be sufficiently above the opening 14 to permit a flow of the lower stratum of the fluid, namely, the milk, as shown in Figure 4.

60 The spout 13 may, in some instances, serve as a finger piece when it is desired to remove the attachment, although, of course, the attachment may be easily removed from the bottle lip by pulling upon the fingers 11.

65 While I have illustrated in the drawings

a cap having the fingers 11, it will be understood that the invention could be embodied in an ordinary pasteboard cap, such as is commonly employed in milk bottles, wherein the cap would be frictionally held in the 70 lip of the bottle.

Moreover, the device could take the further form of an attachment comprising merely a flat cap, without the fingers 11, and including a backing, such as the washer 18, 75 which could be held in position by various means.

Further modifications and alterations may be made in this device without, however, avoiding the scope of the appended claims. 80

What I claim is:—

1. A container closure having a plurality of spaced pouring openings therein, a spout in direct communication with one of said openings, a closure for the other of said openings and means for securing the closure to a receptacle, said spout being directed across the container closure toward the other opening. 85

2. The combination with a milk bottle 90 containing milk and cream in their strata relation, of a closure secured to the bottle having an opening coinciding with a portion only of the opening in the neck of the bottle whereby the bottle may be tilted and the cream discharged through said opening, said closure having a second opening spaced from said first mentioned opening and coinciding with another portion of the opening in the neck of the bottle, whereby milk constituting another and lower stratum when the bottle is tilted may be discharged, means 95 closing said second opening, and a spout communicating with said first mentioned opening and extending across the container closure 100 toward the other opening. 105

In testimony whereof I have hereunto set my hand.

THOMAS N. DERBY.
